GEORGE L. PRICHARD, OF PORT ARTHUR, TEXAS, ASSIGNOR TO GULF REFINING COMPANY, OF PITTSBURGH, PENNSYLVANIA, A CORPORATION OF TEXAS.

CRACKING OILS.

Application filed June 22, 1915. Serial No. 35,617.

This invention relates to cracking oils; dense layer covering the heating element; 55 and it comprises a method of cracking oils wherein a body of petroleum oil is heated under cracking temperature and pressure and where this heating element is the bottom of the still the still bottom fills up and the plates are apt to buckle and warp.

5 while vapors of lower boiling oils are withdrawn and condensed, agitating and advantageously scouring the interior of the still by a device in the still operated by a shaft which passes outside of the still through a

10 packing such as a stuffing box enclosed in a housing, and circulating through the housing a fluid under pressure, advantageously as great as that prevailing in the still and advantageously of the same character as the

15 hydrocarbons being cracked in the still all as more fully hereinafter described and as claimed.

As is well known, when heavy petroleum oils, such as gas oils, petroleum residua, etc., 20 are heated to a high temperature, say above 600 or 650° F., they break down with production of lighter oils, such as kerosene or gasoline; this being the well known "cracking" process. The action is facilitated by

25 operating under pressure. The effects of pressure upon the nature of the reactions are not well understood; it has apparently other actions than that of merely raising the boiling point of the liquid. Cracking has

30 been performed in many types of apparatus but on a practical scale mainly in unobstructed stills externally heated. In the cracking operation, aside from the formation of the lighter products stated, there is

35 always a deposition of carbon and this carbon is in a hard, flinty form. It deposits on the heating elements as a coherent, dense incrustation and not only is its deposition a course of grave inconvenience and expense,

40 since it is hard to remove from the heating elements and causes them to burn through, but it also impedes the operation by impeding the supply of heat. I have found that it also exercises another action; that its

45 presence has a marked influence upon the progress of the operation. This carbon has a catalytic influence in causing the deposition of more carbon; as may be easily perceived from the fact that newly depositing

50 carbon invariably forms on previously deposited carbon. The carbon layer cohering to the heating element steadily builds up, newly formed carbon cohering to that already in existence. The net result is a hard

In the ordinary operation therefore, considering a body of oil under cracking distillation in a steel or iron still heated from the bottom, it will be seen that the oil in the bottom layer is subjected to different influences from that in the top layer in that the oil in the bottom layer is not only subjected to more heat, since it is next the heating element which is hotter than the body of oil, but it is in contact with carbon which is exercising a catalytic effect. The top of the oil body, on the other hand, is cracking under a more uniform and lower heat and substantially in the absence of carbon. Carbon does not appear to form to any great extent save next the heating element, that is, next iron, or next previously formed carbon.

I have found that in cracking oils I can produce very much more uniform results and at the same time attain considerable economies in operation by providing stirring mechanism in the still adapted to produce a constant dissemination of granular carbon or coke through the body of oil. In so doing not only does the stirring keep the temperature of the oil body much more uniform but I find that the coke tends to form in small granules which do not adhere to the heating elements to such an extent as is usual. By keeping these coke granules separate and, as far as possible, uniformly distributed throughout the body of oil, the newly formed carbon or coke tends to deposit on that already in existence; that is, it deposits on the granules or forms new granules. These granules being in every portion of the oil body, the cracking operation goes on much more uniformly and rapidly than is usually the case. Substantially I may say I am performing my cracking throughout the entire body of the oil, instead of, very largely, in the layers immediately in contact with the heating elements. The stirring keeps all the oil uniform in temperature; i. e., the whole body of oil is at the high cracking temperature instead of, mainly, the layer of oil next the heating elements. And it is maintained full of catalytically acting carbon. With the opportunity for the deposition of the excess carbon formed by the presence of the cata-

lytically acting coke granules, there is a greater tendency toward the production of saturated gasoline; something which is highly desirable.

5 It is however substantially impossible to use a stirring mechanism of any kind in the ordinary type of stills and particularly when the still is run under pressure. The walls of a still must be vapor-tight while at the 10 same time the temperatures of oil distillation in the cracking operation are very high. It is difficult to furnish a tight gland or a journal for rotating power-driven elements of a stirrer which shall be both vapor-tight 15 and uniform in engagement at all temperatures. As stated, a cracking still is ordinarily run at temperatures in excess of 600° F. These difficulties are accentuated when the still is run under pressure; say, a pressure of 20 pounds to 300 pounds.

I have however found that by a particular structure of the top of the still, I can maintain the portion of the still body carrying the journaling means and the journaling means themselves at a lower and more convenient temperature than that prevailing in the body of the still. And with these means I can produce a journaling of the shaft which will be tight against liquid 30 and vapor and which is not affected by the temperature of the still; in which the journal bearing has about the same engagement with the shaft whatever the temperature of the still and of the liquid which the shaft-carried means is agitating.

In the accompanying illustration I have shown, more or less diagrammatically, an embodiment of my invention. In this structure

40 Fig. 1 is a view, partly in elevation and partly in vertical section, of a still under this invention;

Fig. 2 is a detailed view on an enlarged scale of the still and stirring means; and

45 Fig. 3 is a diagrammatical showing of a chain stirrer.

In this showing element 1 is a still of cylindrical or other shape and made of any suitable material, such as steel boiler plate. 50 It may be provided with external or bottom firing means 2 of any suitable type. At its top it is provided with vapor outlet 3 leading to an air cooled chamber 4. From this chamber vapor line 5 passes to another air 55 cooled chamber 6 beyond which is outlet 7 provided with loaded valve 8. Conduit 9 takes the vapors to diagrammatically shown condensing apparatus 10 which may be of any usual type. Beyond the condenser is a 60 valve 11 which may be used to cause still pressure to prevail throughout the condenser. Conduit 12 leads into release chamber 13 provided with gage glasses 14 and valved gas pipe 15. This gas release pipe 65 may lead to any suitable means for utilizing

the gas (not shown). Liquid is removed from this tank through valve draw-off 16. The air cooled condensing chambers are provided with run-back 17 communicating with both and leading back into the still.

The bottom 18 of the still may be, as shown, somewhat dished. Across the still at a distance from the bottom is an angle iron bracket 19 supporting a thrust collar, 20. Through this thrust collar passes vertical shaft 21 carrying cross bars 22 to which may be connected chains 23 (see Fig. 3) adapted to sweep the bottom of the still. On the top of the still is plate 24 forming the support for the cooled bearing. On this plate is mounted casing 25. Elements 24 and 25 may be a single casing. This casing is provided with inlet 26 for cooling fluid and outlet 27. This outlet passes to cooling coil 28 in chamber 29 which may contain water or the like and thence to pump 30 which returns cooled fluid to the stated casing. At its top this casing is provided with cover plate 31. As shown, this cover plate is secured in position by bolts and is gasketed to make it removable; but it may be riveted into place. Within the casing is bearing 32 through which the shaft passes. Metallic packing 33 held in place by element 34 is provided, forming a stuffing box. The 95 cover plate carries another bearing 35 also having a good packing 36 around the shaft. At the bottom the still is provided with a draw-off 37 for tar and granular coke. Valve 38 mounted on rod 39 serves to control discharge of tar to the exit 40. The valve rod passes through tubular casing 41 having a screw stuffing box 42 and is operated by lever 43. Motion is given the stirring mechanism by gears 44 from shaft 45. Gage 46 100 may be provided. Outlet 47 (see Fig. 1) may be provided leading to a safety valve (not shown).

In the use of this structure, the still is charged to any desired height with the oil 110 to be cracked or distilled, such as gas oil, petroleum residuum, heavy crude oils, etc. Or a charge of ordinary crude may be placed in the still and distilled until the lighter oils are distilled. If the pressure of the still is 115 not desired in the condenser, valve 8 may be used and valve 11 left open; but if it is desired that the still pressure extend through the condenser, valve 11 may be closed to an appropriate degree and valve 8 kept open. 120 In either event heating is continued until gage 46 shows the desired amount of pressure within the still. During this heating the stirrer is kept in steady movement. When carbon begins to develop, instead of baking on the heating elements, it is formed as loose granular material and is kept circulating through the body of oil. When the desired amount of pressure is attained, valve 8 or valve 11 may be opened to the desired 125

extent and distillation under pressure begun. The pressure is kept at the desired point by adjustment of the firing means and of the reducing valve used. While I may use from 5 80 to 300 pounds pressure, I have found a pressure of about 95 pounds to be most advantageous. During this heating operation oil is kept flowing into the casing 25 through inlet 26 and is discharged through outlet 10 27. This flow of oil keeps the whole bearing at a comparatively low temperature irrespective of the heat in the still. The influence of expansion being removed, a tight joint can be maintained while operating the stirrer. If desired, the oil may be introduced 15 through 26 at a pressure equivalent to that prevailing in the still. If the oil is the same character as that under distillation, it may even be maintained at a somewhat higher 20 pressure so as to make leakage inward. In any event, because of the double packing means 33 and 36, leakage is not to be feared.

The stirrer may advantageously be kept going at a rate of about 30 revolutions per 25 minute.

In lieu of using oil as a cooling means in the journal sealing device 25, any other cooling medium such as water, glycerin, etc., may be used but I regard oil as being, for 30 many reasons, the best material.

The oil flowing through the casing 25 may be kept at any temperature desired.

When the distillation has gone to the desired extent, lever 43 may be lifted, with- 35 drawing plug 38 and allowing the tar and coky carbon in the still to go to exit through 40. The operation of this still may be continuous, discontinuous, or semi-continuous. Where it is desired to introduce oil through 45 out the distillation, this may be done through inlet 48, (see Fig. 1).

What I claim is:—

1. The process of cracking petroleum hydrocarbons which comprises maintaining in 45 a still a body of such hydrocarbons under cracking temperature and pressure while withdrawing and condensing vapors of cracked products, agitating the oil by a stirring device in the still operated by a shaft 50 passing outside the still through a packing enclosed in a closed housing and circulating through the housing a fluid under pressure.

2. The process of cracking petroleum hydrocarbons which comprises maintaining in 55 a still a body of such hydrocarbons under cracking temperature and pressure while withdrawing and condensing vapors of cracked products, agitating the oil by a stirring device in the still operated by a shaft 60 passing outside the still through a packing enclosed in a closed housing and circulating through the housing a fluid under pressure as great as that prevailing in the still.

3. The process of cracking petroleum hydrocarbons which comprises maintaining in a

still a body of such hydrocarbons under cracking temperature and pressure while withdrawing and condensing vapors of cracked products, agitating the oil by a stirring device in the still operated by a shaft 70 passing outside the still through a packing enclosed in a closed housing and circulating through the housing oil under pressure.

4. The process of cracking petroleum hydrocarbons which comprises maintaining in 75 a still a body of such hydrocarbons under cracking temperature and pressure while withdrawing and condensing vapors of cracked products, agitating the oil by a stirring device in the still operated by a shaft 80 passing outside the still through a packing enclosed in a housing and circulating through the housing under pressure oil of the same character as that being cracked.

5. The process of cracking petroleum hydrocarbons which comprises maintaining in 85 a still a body of such hydrocarbons under cracking temperature and pressure while withdrawing and condensing vapors of cracked products, agitating the oil by a stirring device in the still operated by a shaft 90 passing outside the still through a packing enclosed in a closed housing and circulating through the housing oil under pressure as great as that prevailing in the still. 95

6. The process of cracking petroleum hydrocarbons which comprises maintaining in 100 a still a body of such hydrocarbons under cracking temperature and pressure while withdrawing and condensing vapors of cracked products, agitating the oil by a stirring device in the still operated by a shaft 105 passing outside the still through a packing enclosed in a closed housing and circulating through the housing a fluid under pressure while supplying to the still additional hydrocarbons to be cracked.

7. The process of cracking petroleum hydrocarbons which comprises maintaining in 110 a still a body of such hydrocarbons under cracking temperature and pressure while withdrawing and condensing vapors of cracked products, agitating the oil and scouring the internal portion of the still where carbon would tend to deposit by device operated by a shaft passing outside of the still 115 through a packing enclosed in a closed housing, and circulating through the housing a fluid under pressure.

8. The process of cracking petroleum hydrocarbons which comprises maintaining in 120 a still a body of such hydrocarbons under cracking temperature and pressure while withdrawing and condensing vapors of cracked products, agitating the hydrocarbons in the still by a stirring device having a shaft passing outside the still through a packing, maintaining the packing in a closed chamber and controlling the temperature of the packing and the chamber by circulating 125 13.

through the chamber a cooling fluid under pressure.

9. The process of cracking petroleum hydrocarbons which comprises maintaining in a still a body of such hydrocarbons under cracking temperature and pressure while withdrawing and condensing vapors of cracked products, agitating the hydrocarbons in the still by a stirring device having
10. a shaft passing outside the still through a packing, maintaining the packing in a closed chamber, controlling the temperature of the packing and the chamber by circulating through the chamber a cooling fluid under
15. pressure, and during the circulation of such cooling fluid subjecting it to a cooling influence outside of said chamber.

10. The process of cracking petroleum hydrocarbons which comprises maintaining in a still a body of such hydrocarbons under cracking temperature and pressure while withdrawing and condensing vapors of cracked products, agitating the hydrocarbons in the still by a stirring device having a shaft passing outside the still through a packing, maintaining the packing in a closed chamber, controlling the temperature of the packing and the chamber by circulating through the chamber a cooling oil under pressure, and during the circulation of such cooling oil subjecting it to a cooling influence outside of said chamber.

In testimony whereof, I affix my signature.
GEORGE L. PRICHARD.
